(57) **CLAIM**

The ornamental design for a high voltage liquid dielectric test vessel, as shown and described.

DESCRIPTION

FIG. 1 is a perspective view of a high voltage liquid dielectric test vessel according to our design;

FIG. 2 is top view thereof;

FIG. 3 is side view thereof;

FIG. 4 is a bottom view thereof;

FIG. 5 is an end view thereof; and,

FIG. 6 is a bottom perspective view thereof.
